UNITED STATES PATENT OFFICE.

HAROLD MASON DE GRAW, OF NEW LONDON, CONNECTICUT, ASSIGNOR TO ELECTRIC BOAT COMPANY, A CORPORATION OF NEW JERSEY.

BRIDGE FOR SUBMARINES.

1,274,694.

Specification of Letters Patent.

Patented Aug. 6, 1918.

Application filed September 21, 1916. Serial No. 121,366.

To all whom it may concern:
Be it known that I, HAROLD M. DE GRAW, a citizen of the United States, and a resident of New London, in the county of New London and State of Connecticut, have invented certain new and useful Improvements in Bridges for Submarines; and I do hereby declare the following to be a full, clear, and exact description of the invention, such 10 as will enable others skilled in the art to which it appertains to make and use the same.

This invention relates to submarine boats, and provides an improved bridge structure 15 of the collapsible type.

Heretofore collapsible bridges have been employed, but such bridges usually include a plurality of separate parts, which parts, preparatory to submergence, must be detached from each other and from fixed parts 20 of the boat and then stored in more or less remote compartments reached through deck hatches.

The novel bridge structure of the present invention comprises a permanent platform or fixed bridge arranged above the superstructure, in combination with auxiliary platforms and bracing elements which may be folded out of the way when the 25 boat is submerged; the auxiliary platforms and the bracing elements all being permanently attached to the boat at points adjacent to the fixed bridge.

The invention will be most clearly understood from the following description, when taken in connection with the accompanying drawings, of which—

Figure 1 is a top plan view, partially broken away, of the bridge extended; Fig. 40 2 is a side elevation of the bridge extended; Fig. 3 is a section taken on the line 3—3 of Fig. 2; Fig. 4 is a perspective view, on an enlarged scale, showing a detail of construction.

45 A permanent platform or fixed bridge 5 is secured in place on top of the conning tower 6 carried by the hull 7.

Access to the interior of the boat may be had from the bridge by way of a hatch 8 and conning tower 6.

A pair of two-part auxiliary platforms or folding extensions 9 are hinged to the side edges of the fixed bridge 5 as indicated at 10. These side extensions 9 may thus be 55 extended as shown in full lines, or folded

over upon the fixed bridge as shown in broken lines in Figs. 1 and 3. Each side-extension 9 is preferably formed of two separate leaves 9^a and 9^b, these four leaves being each separately hinged to the fixed bridge by its own pair of hinges, so that each leaf may be moved independently of any other thus to facilitate quick changes of the bridge structure from extended to collapsed condition and vice versa. 60

Pivotaly mounted in suitable pockets 11 are a plurality of brackets 12. These brackets are vertically pivoted, and thus, while always extending in a horizontal plane, may be swung out to support the extended side-extensions 9, as shown in full lines, or swung in under the fixed bridge 5, as shown in broken lines in Figs. 1 and 2, when the side-extensions are folded over upon the fixed bridge. 65

The outer ends of the brackets 12 are provided with recesses 13 to register with holes 14 in the side-extensions 9 when the bridge structure is extended. These same recesses 13 register with holes 15 in the side extensions and with holes 15^a in the fixed bridge when the bridge structure is collapsed. Whether the bridge structure is collapsed or extended, suitable pins or bolts may operate with these recesses and holes to lock the brackets and side extensions in place. It is preferred, however, to use the feet of stanchions 16 for the purpose of locking the side extensions to the brackets when the bridge structure is extended; and, in addition to the bolts or pins for locking the brackets in retracted position, to provide suitable latches (not shown) to lock the side-extensions 9 in retracted position. The stanchions 16 are of the familiar type, and 85 support flexible life-lines 17. 90

The pockets 11 are formed in edge-pieces 18, hung below the fixed bridge 5 at opposite sides thereof; these edge-pieces having rounded fore and aft fairwater portions 19. 100 Also, the pockets 11 are so arranged that when the bridge structure is completely collapsed and the brackets 12 are housed in the pockets, the brackets completely fill the pockets, thus making the side edges of the 105 fixed bridge 5 practically flush.

The bridge structure is extended when cruising on the surface, and as thus extended is of great strength and rigidity. When hasty submergence is required, the 110

bridge structure may be entirely collapsed and all parts stowed away or made safely fast, if merely the stanchions 16 and their attached life-lines are removed and passed 5 down the hatch 8, the side extensions 9 are folded over, and the brackets 12 are swung into their pockets 11; all very simple operations which may be quickly performed. As thus collapsed, the entire bridge structure 10 is compact; is inconspicuous when the boat is awash; and may add only a negligible resistance to propulsion when the boat is submerged.

I claim:

15 1. A collapsible bridge structure for submarines comprising, in combination, a fixed bridge, a plurality of side extensions, foldable supporting brackets for the side extensions having stanchion-receiving sockets 20 near their extremities, the side extensions having perforations registering with said

sockets when the parts are extended, and stanchions having end portions adapted to pass through the perforations and into the sockets to secure the parts in extended position. 25

2. A collapsible bridge structure for submarines comprising, in combination, a fixed bridge, a plurality of side extensions hinged to the bridge to fold over on top thereof, 30 foldable supporting brackets for the side extensions having stanchion-receiving sockets near their extremities, the side extensions having perforations registering with said sockets when the parts are extended, and 35 stanchions having end portions adapted to pass through the perforations and into the sockets to secure the parts in extended position.

In testimony whereof I affix my signature. 40

HAROLD MASON DE GRAW.
